METALLIC MOLD

Henry E. McWane, Lynchburg, Va.

Application October 1, 1941, Serial No. 413,214

6 Claims. (Cl. 22—136)

This invention relates to molds and more particularly it has reference to permanent metal molds that will not warp during the casting operation. This application is a continuation in part of my copending case, Serial No. 390,411, filed April 25, 1941.

Practice has shown that while my metal mold may warp .003 to .006 inch the first day in operation, the warping will be progressively less the next two days until finally no further warping is measurable. This is probably due to gradual annealing of the copper face in use until molecular arrangement finally sets. Of course, the warping above referred to is permanent warping, that is, the failure of the mold to return to its original shape and not the temporary warping caused by temperature differences in the metal during pouring.

I have found that there is no heat change in a rigid backing, and if it is of sufficient strength to withstand mechanical strains and is properly "cured," the backing in conjunction with a highly ductile mold face will afford an excellent permanent mold not subject to warpage in the casting processes.

More specifically, my mold comprises a mold face of copper or some other ductile metal and a peripheral backing of a relatively stiff non-ductile metal attached to the back of the mold face. Rigid transverse ribs are connected to the sides of the backing and the upper face of each rib is also fixed to the back of the mold face. Preferably the backing and transverse ribs are welded to the mold face, thus affording a continuous intimate attachment that is particularly efficacious in that it prevents warping of the mold face.

A cover plate is detachably secured to the backing and in combination with the rigid backing forms a water jacket for the mold. Under some conditions, the mold face may be provided with recesses for giving a maximum cooling area to the mold.

An object of this invention is to provide a permanent metal mold that is durable, not subject to warpage and inexpensive to manufacture.

And a further object of this invention is to provide a water jacketed mold with a mold face of a highly ductile metal and a rigid non-ductile ribbed metal backing for the face.

An additional object of the present invention is to provide a permanent metal mold having a ductile mold face and a relatively stiff non-ductile metal backing welded thereto whereby warpage of the face is prevented.

With these and other objects in view, which may be incident to my improvements, the invention consists in the parts and combinations to be hereinafter set forth and claimed, with the understanding that the several necessary elements comprising my invention may be varied in construction, proportions and arrangements, without departing from the spirit and scope of the appended claims.

10 In order to make my invention more clearly understood, I have shown in the accompanying drawings means for carrying the same into practical effect without limiting the improvements in their useful applications to the particular constructions which, for the purpose of explanation, have been made the subject of illustration.

In the drawings:

Figure 1 is a plan view of one half of a mold block constructed according to my invention.

20 Figure 2 is a view similar to Figure 1 showing the complemental mold block.

Figure 3 is a sectional view taken along the line 3—3 of Figure 1 looking in the direction of the arrows and also illustrating the other mold block in its operative position.

25 Figure 4 is a transverse sectional view showing a modified form of mold block that may be employed.

Figure 5 is a bottom view of the mold block illustrated in Figure 3 with the cover plate for the water jacket removed.

Figure 6 is an exploded view illustrating the various parts that constitute the mold.

30 In Figures 1 and 2, I have shown a permanent metal mold 1 comprising complemental mold blocks 1A and 1B. Each mold block is made of a metal of high ductility, such as, copper or cuprous alloys. In other words, the members 1A and 1B must be of a material that will have the property of resisting repeated heatings and coolings without checking or cracking.

35 I have determined that the mold blocks should be relatively thick, and the minimum thickness should be one inch. This structure gives added rigidity to the mold and affords a more even dissipation of the heat. In addition, the danger of fissures extending to the water jacket is minimized materially. When the mold block 1B is disposed on the block 1A to form the complete mold, a molding cavity 2 is defined, as shown in Figure 3.

40 In Figures 3 and 6, it can be seen that a peripheral backing 3 of relatively stiff non-ductile material, for example, iron or cast steel, is welded 50 to the back of the mold block 1A, as indicated at

4. The backing conforms to the shape of the block and is provided with a flange 5 at its outer end. A cover plate 6 is disposed within the flange 5 and bears against a shoulder 7 formed on the flange. A flat member of compressible material 8 of the same size as the plate 6 is located between the plate and the shoulder to afford a seal-tight union between the cover and the backing member 4, and the cover and flat member are secured to the backing 3, by bolts 10. The cover plate 6, the backing 4, and the lower face of the mold part 1A defines a water jacket indicated generally by the numeral 11.

In order to strengthen or reinforce the mold block 1A, it will be observed that a plurality of transversely extending ribs 12 are provided. The ends of each rib 12 are fixed to the sides of the backing 3 and the upper face of each rib is welded to the lower side of the block 1A, as indicated at 13. It should be noted, however, that the lower face of each rib 12 terminates a distance above the compressible material 8 so that the cooling medium in the jacket 11 may circulate freely throughout the water jacket.

Under certain circumstances, it is desirable that a larger cooling surface be provided, and it can be seen that the mold block 1A is formed with a plurality of recesses 15 into which the cooling liquid can flow.

In view of the fact that the mold block 1B is substantially the same in construction as the block 1A, the same reference numerals are used with the exception that they are primed.

From the above description, it is thought apparent that I have provided a permanent metal mold, the ductile mold face of which has attached thereto a rigid non-ductile backing, which, in addition to preventing warping of the mold face, will in combination with the cover plate afford a water jacket for the mold. By having the mold face of a metal, such as copper, the mold face will have the property of resisting the cycles of heatings and coolings without checking or cracking.

By welding the backing and the ribs to the mold face, there is provided an attachment which is continuous and this feature is highly important in that there is afforded a structure which will rigidly support the mold face and prevent distortion in all directions.

In Figure 4, I have shown a mold which is similar to that illustrated in Figures 1 to 3, with the exception that the mold face is relatively thin in cross section, as indicated by the numeral 30. In this embodiment, the recesses for providing a maximum cooling area are omitted, and other than these two distinctions, this mold is similar in construction and operation to the mold part 1A.

It is obvious from the above description that I have devised a permanent metal mold, the mold face of which is not subject to warpage. More

specifically, by providing a relatively stiff non-ductile backing for the ductile face, I am able to prevent the warping of the face during the casting operations.

Moreover, the mold is quite simple in structural details, and can be cheaply and easily manufactured.

While I have shown and described the preferred embodiment of my invention, I wish it to be understood that I do not confine myself to the precise details of construction herein set forth by way of illustration, as it is apparent that many changes and variations may be made therein, by those skilled in the art, without departing from the spirit of the invention, or exceeding the scope of the appended claims.

I claim:

1. A permanent metal mold comprising a ductile mold face, a peripheral backing member attached thereto, transverse ribs connected to the sides of said peripheral backing member, said backing member and ribs preventing warpage of the mold face during the casting operation and a cover plate attached to the peripheral member for forming a water jacket for the mold.

2. A permanent metal mold comprising a ductile mold face, a peripheral backing member welded thereto, transverse ribs welded to the sides of the peripheral backing member and the mold face thereby preventing warpage of the mold face during the casting operation and a cover plate attached to the peripheral member for forming a water jacket for the mold.

3. A permanent metal mold comprising a ductile mold face, a peripheral backing member welded thereto, and transverse ribs welded to the sides of the peripheral backing member and the mold face whereby warpage of the mold face during the casting operation is prevented.

4. A permanent metal mold comprising a mold face of copper, an iron backing welded thereto, and iron transverse ribs welded to the backing and to the mold face whereby warpage of the mold face during the casting operation is prevented.

5. A permanent metal mold comprising a highly ductile mold face, a ferrous backing welded thereto and ferrous transverse ribs welded to the backing and to the mold face whereby warpage of the mold face during the casting operation is prevented.

6. A permanent metal mold comprising a ductile mold face, a peripheral backing member attached thereto, reinforcing means attached to the said peripheral backing member and to the mold face, said backing member and reinforcing means preventing warpage of the mold face during the casting operation, and closure means attached to the peripheral backing member which forms a water jacket for the mold.

HENRY E. MCWANE.
